UNITED STATES PATENT OFFICE.

JAMES T. SMITH, OF NEW YORK, N. Y.

UMBRELLA OR PARASOL CATCH.

SPECIFICATION forming part of Letters Patent No. 366,522, dated July 12, 1887.

Application filed December 15, 1886. Serial No. 221,658. (No model.)

To all whom it may concern:

Be it known that I, JAMES T. SMITH, a citizen of the United States, residing at New York, in the county of New York and State 5 of New York, have invented certain new and useful Improvements in Umbrella or Parasol Catches; and I do hereby declare the following to be a full, clear, and exact description of the invention, such as will enable others to skilled in the art to which it appertains to make and use the same.

My invention relates to spring-retention devices for umbrellas or parasols; and it has for its objects the construction of an improved 15 catch especially adapted for use with solid sticks, to do away with a slot in the finger-piece of the catch and a pin or rivet extending through the same, which are usually employed to hold the finger-piece within the stick, and 20 to dispense with other parts which also are generally employed.

My invention consists of two parts: first, a 25 spring and rivet in one piece, and, second, a stop or rivet adapted to hold the catch in position.

My invention is illustrated in the accompanying drawings, in which—

Figure 1 is a side view of a section of stick 30 with my improvement applied thereto before the same is riveted; Fig. 2, a longitudinal section of the same; and Figs. 3, 4, and 5, details.

In the drawings, A is the spring finger bar 35 or catch, made of sheet metal. It is turned at a right angle at one end to form a prong, b. At the opposite end it is provided with a shoulder, C.

D is a space cut in the stick, of a form

adapted to receive the spring-bar A. The bar is inserted in the space D, and the prong 40 b driven through the stick or passed through a hole drilled for that purpose. In Fig. 1 this prong is shown as extending a considerable distance beyond the stick. When so extended, the excess may be cut off and a rivet formed 45 of the end to retain the spring in the stick.

E is a stop-pin having a head, e, and is driven or otherwise passed through the stick until the head e rests upon the shoulder C of the catch. When the pin E is of such length 50 that it extends through and beyond the stick, the excess may be cut off and the pin riveted against the stick.

By my invention the employment of separate and detachable springs to give elasticity 55 to the catch is dispensed with, and also inner casings or a slotted plate to hold the catch in place is unnecessary.

What I claim is—

A runner-holder consisting of a stiff metal 60 spring finger-bar, A, having at one end a prong, b, adapted to extend through the stick and be riveted thereto, and at the opposite end a shoulder, C, in combination with a brad-shaped pin, E, adapted to extend through the 65 stick and be riveted thereto, with its lip resting upon the said shoulder, to hold the catch in place without other holding devices, substantially as described.

In testimony whereof I affix my signature in 70 presence of three witnesses.

JAS. T. SMITH.
